[57] CLAIM

The ornamental design for a solenoid cylinder frame for reciprocating motor.

DESCRIPTION

FIG. 1 is a perspective view of a solenoid cylinder frame for reciprocating motor;

FIG. 2 is a top plan view thereof;

FIG. 3 is a side elevational view thereof;

FIG. 4 is a bottom plan view thereof;

FIG. 5 is an inverted opposite side elevational view of the view of FIG. 3, and

FIG. 6 is an inverted front elevational view thereof.
